(57) **CLAIM**

I claim the ornamental design for combined green repair tool with USB, as shown and described.

DESCRIPTION

FIG. 1 is a perspective view of a combined green repair tool with USB showing my design;

FIG. 2 is a side view thereof;

FIG. 3 is a front edge side view of the design;

FIG. 4 is a bottom side view of the design;

FIG. 5 is a top side view of the design;

FIG. 6 is an exploded perspective view of the design;

FIG. 7 is an exploded top side view of the design;

FIG. 8 is an exploded bottom side view of the design;

FIG. 9 is an exploded side view of the design;

FIG. 10 is a back side view of the design; and,

FIG. 11 is an exploded bottom perspective view of the design. The broken lines shown in the drawings represent portions of the combined green repair tool with USB that form no part of the claimed design.
